UNITED STATES PATENT OFFICE

2,509,268

SASH CONSTRUCTION

Edwin J. Grunwald, Brooklyn, N. Y., assignor to
The Alumilime Corporation, Brooklyn, N. Y., a
corporation of New York

Application September 16, 1946, Serial No. 697,195

2 Claims. (Cl. 20—56.4)

1

My invention relates generally to window pane supports, and in particular it relates to an apparatus for supporting a sheet or pane of relatively frangible and brittle material such as glass and the like. More particularly my invention relates to the draw bar component and its associated parts in devices of this character, which comprise generally a front section and a back section between which the sheet or pane of glass is disposed, and a draw bar means to grip and hold the sheet or pane of glass between the sections.

The main object of my invention is the provision, in a device of the character described, of a draw bar of resilient material.

Another object of my invention is the provision, in a device of the character described, of a draw bar of resilient material and means to place same under tension.

Still another object of my invention is the provision, in a device of the character described, of a draw bar of resilient material and means to place same under tension by exerting pressure on one end thereof to bring the front and rear sections together on opposite sides of the supported member.

Still another object of my invention is the provision of a draw bar comprising a pair of wing sections, an arm extending therefrom, the end-most portion of said arm being bent over at an angle with respect to the body of said arm, the end being resiliently offset with respect to said body.

Still another object of my invention is the provision of a draw bar having a compressible end portion, the compression at said end serving to place the bar under tension to urge the attached front member towards the rear member as a result thereof.

Still another object of my invention is the provision of a draw bar having an enlarged end portion formed of a bent over terminal portion, and an inclined plane in the front pane supporting member, means to urge the bent over terminal portion down the incline, said means also reducing the enlargement and tensioning the draw bar.

Other and further objects of my invention will in part be obvious, and still others will be apparent from the following description of an illustrative embodiment thereof.

In the drawings annexed hereto and forming a part hereof,

Figure 1 is a part perspective, part sectional view of one form of device constructed according to and embodying my invention; and

2

Figure 2 is a perspective view of the draw bar component thereof.

My device as a whole comprises a front member 10 and an interfitting rear member 12. These members 10, 12 are disposed atop a fixed support, as 14, secured to the window opening in the building walls as 15. Members 10, 12 may be formed as by extruding or stamping or molding same, but I have found extruded aluminum to be well suited for my purposes.

Front member 10 is curved inwardly from the center 16 thereof, the lower end 18 being provided with a convex beading 20, and the upper end 22 being provided with a rounded tip 24. On the inner aspect of front member 10, there is provided a socketed recess or channel 26, defined by a pair of laterally and inwardly extended shoulders 28, 28.

Rear member 12 has a rear vertical wall portion 30, an inwardly directed shelf 32 at the top thereof, and an inwardly directed floor portion 34 at the bottom thereof. Floor 34 rests atop the support framing 14. Floor 34 is extended inwardly beyond the lip 36 of shelf 32, and as seen in Figure 1, the lip 36 of shelf 32 is convexly curved. Floor 34 at the end of its reach 40 is concaved as at 42, to receive therewithin the convexly curved bead 20 of the front member 10. The floor 34 rises and angles upwardly and inwardly as at 44, defining an inclined slide towards the rear of the device.

Suitably located along the length of each rear member 12, and in the shelf portion 32 thereof, I provide a plurality of threaded apertures 50, angled slightly towards the point where floor 34 meets the rise of incline 44. A corresponding threaded bolt 52 is provided for each opening 50, bolts 52, 52 being of sufficient length as to reach down almost to floor 34 and extend upwardly of shelf 32 so that it may be engaged by a suitable turning tool, as a screwdriver or the like.

The draw bar 60 component of my device is formed of springy Phosphor bronze, or stainless steel material, as by stamping or otherwise and comprises a butt portion 62, a body portion 64 and a head portion 66. Butt 62 has a central straight portion 70, and a wing portion 72, 72 at each end thereof bent outwardly therefrom. Body 64 comprises a flat strip 74 as wide as center portion 70, and extending therefrom at right angles thereto. Head 66 may be integral with strip 74 and in line therewith and is spaced therefrom by a crimp line 76 extending the width of the strip 74, the head itself comprising a portion 80 in line with strip 74 and a bent over wing

82 downwardly and inwardly angled from portion 80, the terminal portion 84 of which wing 82 is bent upwardly towards the underside of strip 74 and in line with crimp 76. The point of angulation between portion 80 and wing 82 is also crimped as at 86, in lateral alignment with crimp 76, so that portion 80 between crimps 76, 86 constitutes the floor of a channel which is in vertical alignment with opening 50 in shelf 32. As seen in the drawings, draw bar 60 is formed of relatively light gauge springy material, and is of such length as to extend almost from the front to the back members on their inner aspects.

In use, the butt portions 62, 62 of the draw bars are keyed into channel or recess 26, the angulated wing portions 72, 72 thereof, in bearing against the floor of the channel, serving to prevent side slipping thereof. Bead 20 of front member 10 is disposed against concaved recess 42 in rear member 12, and then the sheet M of material to be supported is disposed between the spaced pairs 24, 36 of the upper ends of the front and back members. A plurality of threaded bolts 52, 52 are then inserted in openings 58, and worked downwardly until the bottom end 90 thereof engages the channel or groove 80 in the upper portion of draw bar head 66. As the bolt 52 is worked downwardly, head 66 is forced downwardly until wing 82 bears against incline 44. The butt portion 62 is locked within socket 26, and as body 74 and head 66 of the draw bar are moved downwardly under bolt 52, the front member 10, at the upper portion 22 thereof is drawn towards plate M, pressing same against the opposed end 36 of the rear member 12, front 10 pivoting at 20, 42 about the foot of rear member 12. As bolts 52, 52 are threaded downwardly still further, wing 82 riding down incline 44, will be forced towards the underside of crimp 76. The resilient pressure thus exerted will hold the plate M firmly between the curved tips 24, 36 of the front and rear members. There may permissibly be only very slight flexion between the body 74 of the draw bar and the butt 70 thereof but not so much as to prevent downward movement of the head portion from being almost directly

transmitted to the channel-held butt 70 and to the front portion 10.

My draw bar is simple to construct, and may be stamped out with not too complicated machinery. It is easy to install and operate, and with it, the interposed sheet M will be held firmly with resilient pressure.

Having now described my invention, what I claim and desire to secure by Letters Patent is:

1. A draw bar of thin gauge spring metallic material comprising a flat butt portion, an elongated flat body portion extending from the butt and at right angles thereto, a head portion in line with the body having at the outer end thereof a wing portion extending downwardly from and reversely of the head and terminating in a short leg portion reaching upwardly towards and at right angles to the body, the butt portion having a flat integral wing at each end thereof angled outwardly therefrom.

2. A draw bar of thin gauge spring metallic material comprising a flat butt portion, an elongated flat body portion extending from the butt and at right angles thereto, a head portion in line with the body having at the outer end thereof a wing portion extending downwardly from and reversely of the head and terminating in a short leg portion reaching upwardly towards and at right angles to the body, the head portion being crimped to provide a transversely extending groove opening from the underside thereof, into which groove the short leg portion extends on compression of the head, the grooves defining the direction of extension and limit thereof.

EDWIN J. GRUNWALD.
